UNITED STATES PATENT OFFICE.

FRANK DANIEL TELLIN, OF KALONA, IOWA.

METAL-BASKET CORRUGATOR.

1,275,497.

Specification of Letters Patent. Patented Aug. 13, 1918.

Application filed April 8, 1918. Serial No. 227,198.

To all whom it may concern:

Be it known that I, FRANK DANIEL TELLIN, a citizen of the United States, residing at Kalona, in the county of Washington and 5 State of Iowa, have invented certain new and useful Improvements in Metal-Basket Corrugators; and I do hereby declare the following to be a full, clear, and exact description of the invention, such as will 10 enable others skilled in the art to which it appertains to make and use the same.

This invention relates to the manufacture of corrugated metal baskets, wherein the ribs of corrugation extend vertically with 15 respect to the vessel, the lower portion of which is curved inwardly by excess of corrugation, and the basket is both shaped and stiffened thereby.

This invention involves a novel method of 20 procedure in the formation of the basket, and improved mechanism whereby such method is carried into effect.

The invention is fully disclosed in the description and claims following, reference 25 being had to the accompanying drawing, in which:

Figure 1 is a side elevation of a machine embodying my invention, partly in section, the section of the base being 1-1; the forming die and connected parts being $a-a$, and the middle of the die-supporting table, $b-b$.

Fig. 2 is a plan view of the die, forming levers and lever-actuating spider, below the 35 line 2-2. Fig. 3 is a front view showing the lower portion of the main frame, the driving and feed mechanism, and the basket blank in position for formation, but with the forming parts removed. Fig. 4 is a side 40 view, partly in mid-section, illustrating a modified type of machine, and provided with a turn-table for a double set of forming mechanisms, whereby the operator may remove the finished product and supply a 45 new blank while the forming machine is in operation.

In the drawing, the numeral 5 denotes the main frame of a press of a familiar type, having a base 6, standard 7, overhanging arm 8 and a support for the forming die to be described presently. The ram 9, which carries a suitable device for actuating the corrugating levers 10, is here shown connecting by links 11 with the main 50 operating lever 12, pivoted at 13, and connecting by a rod 14 with a crank 15. This 55 is attached to a shaft 16 provided with a large gear 17 meshing with a pinion 18 mounted loosely on a shaft 19 driven by a belt-wheel or pulley 20. The pinion forms 60 half of a clutch, the other half 21 of which is splined slidably on the shaft. To this is connected a bell-crank lever 22, provided with a clutch-releasing spring 23. A foot-lever 24 co-operating with the bell-crank 65 lever serves to engage the clutch. When in action the ram has a reciprocating vertical motion, as will be evident.

The blank 25 out of which the basket is formed is first formed as a simple cylinder, 70 open at both ends, and usually of galvanized sheet steel. This may be formed to approximately hemispherical shape at one end by corrugating lengthwise of the cylinder, the corrugations deepening toward the edge 75 thereof, provided such corrugations be made over a suitable form and by means of a properly formed corrugating instrument. This has usually been done by the successive formation of single corrugations. My improved method employs a gang of corrugators equal to the whole series of corrugations, and the impressing of the whole series by a succession of steps in the position of the blank, whereby the corrugations are gradually deepened, and increasingly toward the 85 end of said blank.

Referring to Figs. 1, 2 and 4, the numeral 26 denotes the die or matrix over which the basket is formed. This is shown as a cylindrical body whose open lower end rests on the table 27 (Fig. 1) or 59 (Fig. 4). Its upper end is curved to approximately semi-circular form, and is provided with a series of radial grooves, as best shown in Figs. 2 and 90 4. The matrix is grooved at 29 to receive the grippers of a feed device to be described presently. Outside the matrix is mounted a ring 30, in the radially slotted upper part of which is mounted the gang of corrugating levers, 95 4. The matrix is grooved at 29 to receive the grippers of a feed device to be described presently. Outside the matrix is mounted a ring 30, in the radially slotted upper part of which is mounted the gang of corrugating levers, 100 whose operating edges 32 coincide with the curvature of the matrix grooves, it being understood that these edges are somewhat rounded, and are thin enough to enter the grooves together with the crimped sheet 105 metal on each side. It will be evident that the corrugations are formed by the pinch of these levers as they are rocked from the positions shown in Figs. 1 and 4 to a position not shown, closed down over the top of 110 the matrix. This movement of the levers may be effected by either pulling up on the

extended arms 33, as in Fig. 1, or by pressing down the curved forming blades as shown in Fig. 4, by means of a bowl-shaped presser-head 34, which latter may connect 5 directly with the ram. In the former case the preferred construction is to connect the outer levers with a continuous ring 35 mounted in slots 36 in said arms. The ring connects by link-rods 37 with a cross-bar 38 10 secured to the ram. This should preferably be a three-armed cross-bar or spider, so as to prevent any possible tipping of the ring.

The corrugations are formed by a series 15 of crimping actions beginning at the upper edge of the blank. After each pressing impulse the blank is advanced upwardly, and at the next succeeding pressure the grooves are deepened and somewhat curved inwardly, until finally the form is substantially 20 as shown in Fig. 4 at the left. The feed mechanism for this purpose is shown fully in Figs. 1 and 3, and in modified form in Fig. 4. The former will be first described.

A yoke 39 is provided at its upper ends 25 with gripping jaws 40, which when partially closed hold the edge of the blank between them. This closure is effected by the constriction of the passage 29, which is enlarged at 29^a to allow the grippers to open to receive 30 the blank. The tension on the grippers in this groove may be sufficient to support the yoke by friction, in which case no detent pawl is needed. The upward movement step by step is effected by a ratchet-bar 35 41 connecting with a lever 42 pivoted at 43, and at its other end connecting by a link-rod 44 with one of the corrugating levers. It will be seen that the pawl retreats as the corrugating levers move to crimping position, and vice versa. In its upward movement the teeth of the pawl successively engage a stop-plate 45 mounted slidably on a vertical guide 46, the plate being held to working position by a keeper 47 attached to 40 the yoke. To this guide is attached a crank 48, which is pushed positively to position to disengage the plate by a rod 49 connecting with the bell-crank lever above described. It is held yieldably to engaging position by 45 a spring 50. To forcibly draw down the yoke from its extreme upward position to the initial position shown, a link-rod 51 connects the yoke with a foot-lever 52. In Fig. 4 is shown a detent pawl 53 provided with 55 a tail 54, which serves for engagement by gravity with a notched plate 55 attached to the yoke. When the turn-table is turned, this pawl is automatically disengaged by a cam 56, permitting the yoke to drop by gravity, if the grippers will permit it to do so, or to be drawn down forcibly by the foot lever, as just described.

Referring to Fig. 4 it will be seen that 60 the main frame is provided with a hollow pivot-post 57, and on this is mounted a

turn-table carrying a pair of forming mechanisms. A bracket 58 serves as a support for the inner end of the turn-table 59. The turn-table is held to accurate working position by a dog 60 pivoted to the bracket, and connecting by a link-rod 61 with a hand-lever 62. The feed mechanism is in the main similar to that above described, but is made to disengage, so as to allow the turning of the turn-table. The ratchet-bar has an open 75 connection at 63 with the lever 42. The link-rod 44 has also an open connection with the corrugating lever at 64, embracing a little more than half of a circular knob 65 on said lever. The link-rod is held to proper registering position by a spring 66. This, as will be evident, allows for the engagement and disengagement of the feed mechanisms by merely turning the turn-table. A stop-pin 80 supports the ratchet-bar at its lowermost 85 position.

The operation of the machine is briefly described as follows:

With the machine in the position shown, 90 the operator places the cylindrical blank in position, its upper end projecting somewhat into the corrugating zone. He then starts the machine by depressing the starting lever, and the same operates continuously until the lever is released. Succeeding the pressing 95 action, the feed mechanism advances the cylinder upwardly one notch of the ratchet, and the operation is repeated, until the cylinder or blank has reached to upward limit of its movement. The machine is then 100 stopped by releasing the starting lever. This also disengages the feed, and permits the grip pins being stripped from the lower edge of the corrugated blank, which may then be lifted off the matrix and replaced 105 by a new blank.

No attempt has been made herein to represent the machine with mechanical exactness, but the main principles and operative 110 features of the machine are clearly indicated. In practice the number of corrugations in an ordinary bushel basket is greater than herein shown, but this and other minor features of construction have been disregarded.

Having thus described my invention, I claim:

1. In a metal basket corrugating machine, 115 a radially fluted matrix, a gang of coinciding corrugators, means to impart to them intermittent motion in and out of said flutes, and means adapted to hold a cylindrical blank in position around said matrix, and to advance it endwise intermittently, and between the strokes of the corrugators.

2. In a metal basket corrugating machine, 120 a matrix having an approximately hemispherical forming surface, fluted radially, a gang of correspondingly curved corrugators pivoted to swing in and out of said 125

130

flutes, a support therefor, means adapted to actuate said corrugators, means adapted to hold a cylindrical blank, and feed mechanism to advance the blank step by step toward the operating ends of the corrugators.

3. In a metal basket corrugating machine, a radially fluted matrix, a support therefor, a surrounding, lever-carrying ring spaced away from the matrix, a gang of corruga-

10 tors pivotally mounted thereon, means adapted to actuate said corrugators, grippers to engage the lower edges of a cylindrical blank, and feed mechanism adapted to advance said grippers and blank between

15 crimping impulses of the corrugators step by step, and successively widen the crimped zone.

4. In a metal basket corrugating machine, a matrix having radial flutes converging to-

20 ward one end, a gang of coinciding corrugators, means to impart intermittent radial movement thereto, and feed mechanism to advance the basket blank intermittently between the strokes of the corrugators, and a

25 less distance than the space covered by their working faces, whereby the impressions of the corrugators are made to progressively overlap.

5. In a metal basket corrugating machine,

30 combined with a matrix and corrugators,

substantially as described, a feed mechanism comprising grippers adapted to seize the end of the basket blank not presented to the corrugators as the blank is advanced, an intermittent, step-by-step feed, and means 35 whereby the grippers may open to receive a new blank, when in the initial position.

6. In a metal basket corrugating machine having a matrix and corrugators substantially as described, a feed device provided 40 with grippers to hold one end of the basket blank, means adapted to close said grippers on the metal and to support the feeding device frictionally, means to advance the feed device step by step, and means adapted to 45 forcibly strip the grippers from the blank when in its advanced position.

7. In a metal basket corrugating machine having a matrix radially fluted and a gang of coöperating pivoted levers surrounding 50 the matrix, a feed mechanism adapted to advance the basket blank step by step, and a connection of said feed mechanism with one of the corrugating levers.

In testimony whereof I affix my signature 55 in presence of two witnesses.

FRANK DANIEL TELLIN.
